CLAIM

The ornamental design for a faucet handle, as shown and
described.

DESCRIPTION

FIG. 1 is a perspective view of a wall-mounted faucet handle
showing my new design;

FIG. 2 is a front view of the embodiment shown in FIG. 1;
FIG. 3 is a rear view of the embodiment shown in FIG. 1,
wherein the central portions of the rear of the handle are
reduced to broken lines.

FIG. 4 is a left side view of the embodiment shown in FIG. 1;
FIG. 5 is a right side view of the embodiment shown in FIG.
1;

FIG. 6 is a top view of the embodiment shown in FIG. 1; and,
FIG. 7 is a bottom view of the embodiment shown in FIG. 1,
wherein the circular shape shown on the bottom of the handle
is reduced to broken lines.
